GOLF BALL

Robert F. Smith, Detroit, Mich., assignor to
Leonard A. Young, Detroit, Mich.

Application January 8, 1938, Serial No. 183,990

10 Claims. (Cl. 273—62)

This invention relates to improvements in golf balls.

The main objects of this invention are to provide a golf ball which is highly efficient as to distance and accuracy of flight, may be economically produced, and is very durable.

A further object is to provide a golf ball having these advantages which may be manufactured with great uniformity and to meet varying conditions as to hardness or "feel" and the qualities incident thereto.

Objects relating to the details and economies of the invention will appear from the description to follow. The invention is defined and pointed out in the claims.

A preferred embodiment of the invention is illustrated in the accompanying drawing, in which:

Fig. 1 is a section considerably enlarged of a golf ball embodying my invention.

Fig. 2 is an inside view of one of the outer molded lamina or layer segments.

Fig. 3 is an inside view of one of the intermediate lamina or layer segments.

Fig. 4 is an inside view of one of the inner lamina or layer segments.

Fig. 5 is a fragmentary view partially in section of a modified form or embodiment of my invention.

In the manufacture of golf balls now commonly regarded as standard type, the body of the ball is formed of a core deemed suitable upon which there is a winding of rubber strands under tension. A cover, usually of balata, is applied to this body. In the manufacture of such balls, the winding operation and also the material is expensive and requires great care in order to produce an approximately uniform product. Care must be taken to provide a core or to treat the core so that it is not distorted during the winding. Further, the severe usage which a golf ball receives when subjected to the impacts of severe blows tends to and frequently does displace the winding to a greater or less extent with a result that the ball becomes out-of-round or out-of-balance and its usefulness is thereby impaired.

My invention, in one phase of it, eliminates entirely the winding operation with the consequent expense and difficulty and inaccuracy in manufacture and the invention produces a ball which is very unlikely to have any of its component parts displaced in use except that the cover may be cut or injured.

In another embodiment, the winding is very materially reduced and such winding as is pres-

ent is upon a firm body so that it is unnecessary to take preliminary steps to prevent the body upon which the winding is placed, becoming distorted or out-of-round during the winding step.

In the embodiment of my invention illustrated in Figs. 1 to 4 of the drawing, the body of my improved ball comprises the inner layer 1, the outer layer 2, the intermediate layer 3, and the cover 4, the cover being molded directly upon the outer layer 2. The layers 1, 2 and 3 are of molded rubber and in the embodiment illustrated are formed of pairs of hemispherical sections 5, 6 and 7 having rabbeted joints 8 or interfitting tongue and recess joints secured together by a cement 9, preferably a rubber latex cement.

The outer layer is provided with a multiplicity of air pockets 10 uniformly spaced. These pockets are formed as the segments are molded, the outer ends of the segments being closed. It will be understood that the number of pockets shown may be varied and that in the drawing they are shown spaced for convenience and clearness in illustration. The segments of the intermediate layer are provided with similar pockets 11. When the layers are arranged in concentric relation, the inner ends of the pockets are sealed or substantially sealed by the adjacent inner layer.

In forming the ball, the core fluid 12, preferably honey, is frozen in a mold into spherical form and the segments forming the body are then successively assembled and cemented together. The cover which is preferably of balata is molded upon the outer layer 2 which has a roughened surface 13 with which the cover material interlocks as is well understood when cover material is molded upon a strand-wound body.

In Fig. 5, an outer layer of tension-wound rubber strands 14 is applied to the outer molded layer, the cover 4 being molded upon this strand-winding. In this embodiment, the body has the appearance of a strand-wound body.

The outer layer 2 is preferably of quite hard rubber, at least of a hardness approximating that of a strand-wound body. The inner layer 45 or lamina 1 is preferably of relatively soft rubber and the intermediate layer of a hardness intermediate the outer and inner layers.

The rabbeted edges of the segments not only facilitate the ready assembling of the layers but they effectively receive and retain the cement as the segments are brought together and serve as guiding and positioning means during the assembling operation.

My improved balls may be manufactured with

great uniformity and very economically. The hardness of the various layers may be very accurately controlled to produce balls having the desired characteristics.

5. Balls embodying my improvements are very durable and have long range or flights, the air pockets adding very materially to the distance or flight as compared to a ball which does not have this feature. As I have pointed out, the number 10 and location of the air pockets may be very greatly varied and it will be understood that I have not attempted accuracy in respect to either the relative size or number or location of the air pockets.

15. I have not attempted to illustrate or describe certain other embodiments or adaptations which I contemplate as it is believed that this disclosure will enable those skilled in the art to embody or adapt my improvements as may be desired.

20. Having thus described my invention, what I claim as new and desire to secure by Letters Patent, is:

1. A golf ball comprising a body portion consisting of a plurality of concentric fitting layers 25 of molded rubber, each layer comprising hemispherical segments having rabbeted interfitting edges joined by rubber cement, the outer and intermediate layers having a multiplicity of air pockets molded therein, the radial dimension of 30 each of said pockets being less than the thickness of the respective layers in which they occur, the inner ends of the air pockets being closed by the next adjacent layer, the inner layer being of relatively soft rubber and filled with a core 35 material and constituting the core of the ball, the outer layer being substantially thicker than the other layers and of relatively hard rubber, the intermediate layer being of an intermediate hardness as compared to the inner and outer 40 layers and the outer layer having a roughened surface, and a cover molded upon said ball body and interlocking with said roughened surface of said outer layer.

2. A golf ball comprising a body portion consisting of a plurality of concentric fitting layers 45 of molded rubber, each layer comprising segments having cemented interlocking joints, the outer and intermediate layers having a multiplicity of air pockets molded therein, the inner 50 ends of the air pockets being closed by the next adjacent layer, the inner layer being of relatively soft rubber and filled with a core material and constituting the core of the ball, the outer layer being substantially thicker than the other layers and of relatively hard rubber, the 55 intermediate layer being of an intermediate hardness as compared to the inner and outer layers and the outer layer having a roughened surface, and a cover molded upon said ball body and interlocking with said roughened surface of said outer layer.

3. A golf ball comprising a body portion consisting of a plurality of concentric fitting layers 60 of molded rubber, the layers being of increasing hardness in outward progression, each layer comprising hemispherical segments having rabbeted interfitting edges joined by rubber cement, the outer and intermediate layers having a multiplicity of air pockets molded therein, the inner 65 ends of the air pockets being closed by the next adjacent layer, the radial dimension of each of said pockets being less than the thickness of the respective layers in which they occur, and a cover molded upon said ball body.

75. 4. A golf ball comprising a body portion con-

sisting of a plurality of concentric fitting layers of molded rubber, the layers being of increasing hardness in outward progression, each layer comprising segments having cemented interlocking joints, the outer and intermediate layers having a multiplicity of air pockets molded therein, the inner ends of the air pockets being closed by the next adjacent layer, the radial dimension of each of said pockets being less than the thickness of the respective layers in which they occur, and a cover molded upon said ball body.

5. A golf ball comprising a body portion consisting of a plurality of independently formed and fitting layers of molded rubber, the layers being formed of hemispherical segments and having annular tongue and recess cemented edge joints, the outer and intermediate layers having a plurality of air pockets at their outer ends molded therein and open at the front surface of the layers only, the outer layer being of a hardness approximating that of a rubber strand wound ball, the inner layer constituting a hollow core and having a fluid filling, a layer of rubber strands tension-wound upon said outer molded layer, said outer molded layer having a roughened surface for anchoring the strands of the winding, the intermediate and inner layers being of substantially less hardness than the outer layer, and a cover molded on said winding.

15. 6. A golf ball comprising a body portion consisting of a plurality of independently formed and fitting layers of molded rubber, said layers being graduated in hardness, the layers having cemented edge joints, the outer and intermediate layers having a plurality of air pockets at their outer ends molded therein and open at the inner surface of the layers only, a layer of rubber strands tension-wound upon said outer molded layer, and a cover molded on said winding.

30. 7. A golf ball comprising a body portion having a plurality of concentric fitting molded rubber layers united in a substantially integral structure, the inner layer being filled with fluid and constituting a core, the several layers being formed of hemispherical segments and having rabbeted cemented joints, at least one of the layers having a multiplicity of air pockets molded into the same and uniformly distributed, the outer ends of all the air pockets being closed, their inner ends being substantially closed by the abutting layer, the inner layer being of relatively soft rubber, the outer layer being of relatively hard rubber and having a roughened surface, a layer of tension-wound rubber strands on said outer molded layer, and a cover of balata 35 molded upon said winding.

40. 8. A golf ball comprising a body portion having a plurality of concentric fitting molded rubber layers of graduated hardnesses united in a substantially integral structure, the several layers being formed of segments and having cemented joints, at least one of the layers having a multiplicity of air pockets molded into the same and uniformly distributed, the outer ends of all the air pockets being closed, their inner ends being substantially closed by the abutting layer, a layer of tension-wound rubber strands in said outer molded layer, and a cover molded upon said winding.

45. 9. A golf ball comprising a body portion having a plurality of concentric fitting molded rubber layers united in a substantially integral structure, the inner layer being filled with fluid and constituting a core, the several layers being formed of hemispherical segments and having 50

rabbeted cemented joints, at least one of the layers having a multiplicity of air pockets molded into the same and uniformly distributed, the outer ends of the air pockets being closed, their inner ends being substantially closed by the abutting layer, the inner layer being of relatively soft rubber, the outer layer being of relatively hard rubber and having a roughened surface, and a cover molded upon said outer layer.

5 10. A golf ball comprising a body portion having a plurality of concentric fitting molded rub-

ber layers of graduated hardnesses united in a substantially integral structure, the several layers being formed of segments and having cemented joints, at least one of the layers having a multiplicity of air pockets molded into the same and uniformly distributed, the outer end of each of the air pockets being closed, their inner ends being substantially closed by the abutting layer, and a cover molded upon said outer layer.
